[57] CLAIM

The ornamental design for a baby bier and cremation urn stand, as shown and described.

DESCRIPTION

FIG. 1 is a front, top and right side perspective view of a combined baby bier and cremation urn stand showing our new design; the broken line showing is for environmental purposes only and forms no part of the claimed design;

FIG. 2 is a right side elevational view, the opposite side being a mirror image; and,

FIG. 3 is a front, top and right side exploded perspective view thereof showing.

FIG. 1***FIG. 2*****FIG.3**
